UNITED STATES PATENT OFFICE

150,264

DESIGN FOR A DOLLY FOR TRANSPORTING AIRPLANES OR THE LIKE

Mahlon C. Snyder, Hamburg, N. Y.

Application July 1, 1947, Serial No. 140,041

Term of patent 14 years

(Cl. D14—3)

To all whom it may concern:

Be it known that I, Mahlon C. Snyder, a citizen of the United States, residing at Hamburg, in the county of Erie and State of New York, have invented a new, original, and ornamental Design for a Dolly for Transporting Airplanes or the like, of which the following is a specification, reference being had to the accompanying drawing, forming part thereof.

In this drawing:

Fig. 1 is a top plan view of a dolly for transporting airplanes or the like, showing my new design.

Fig. 2 is a bottom plan view of the same.

Fig. 3 is a side elevation of the same.

Fig. 4 is a front end view thereof.

Fig. 5 is a rear end view of the same.

Fig. 6 is a vertical cross section taken on line 6—6, Fig. 3.

I claim:

The ornamental design for a dolly for transporting airplanes or the like, as shown.

MAHLON C. SNYDER.
